UNITED STATES PATENT OFFICE.

JOANNES PIAT, OF LYON, FRANCE.

CARBURETEE.

1,371,931.

Specification of Letters Patent. Patented Mar. 15, 1921.

Application filed April 16, 1919. Serial No. 290,532.

To all whom it may concern:

Be it known that I, JOANNES PIAT, a citizen of the French Republic, residing at Lyon, France, have invented certain new and useful Improvements in Carbureters, of which the following is a specification.

This invention relates to carbureters more especially of the type described in my application for United States patent, Serial No. 104412 filed 19th June, 1916.

In the said carbureter the slow-running device comprises a sliding plug or valve which is adapted to descend upon and envelop the jet and has a cavity into which the jet projects when the valve is in its lower positions with a reduced passage from said cavity for supplying the fuel mixture to the engine manifold. When the valve has been raised sufficiently to be clear of the jet the latter discharges into a mixing chamber to which the air has access through or between two pivoted gravity controlled flaps.

One of the objects of the present invention is to modify the means of control of the air admission to the mixing chamber more particularly in order to render its action more sensitive and to obviate the effect of lag in the action of the flap valve at the commencement of their entering into function, more especially when the carbureter is operating in a comparatively rarefied atmosphere as for example on an aeroplane at a high altitude.

For this purpose I provide in place of such pair of flap valves, a single laterally placed flap valve which tends to close under the action of gravity and to open under suction of the motor, this flap valve having or not as may be desired, means for adjusting the position of its center of gravity.

I further provide means for counteracting the influence of this flap valve when the motor is required to furnish full power at an altitude where the density of the atmosphere is insufficient to maintain the flap valve fully open against the effect of gravity thereon, such means being so connected that it is operated by the movement of the throttle or of the valve which governs the passage of fuel mixture to the engine.

The invention further comprises details of improvement hereinafter described and more particularly pointed out in the claims.

In the annexed drawings:—

Figure 1 is an elevation of the improved

carbureter as seen from the front side on which the hinged flap valve is placed,

Fig. 2 is a plan view of Fig. 1 with the flap valve, air entrance hood and flap valve controlling devices removed.

Fig. 3 is a vertical section on line 3—3 of Fig. 1 with the flap valve removed.

Fig. 4 is a section similar to Fig. 3 but showing the means for controlling the flap valve in diagram only, the position of the flap valve when out of action being shown in dotted lines, the left of the figure is a section on line 4—4—4—4 of Fig. 1 looking in the direction of the arrows.

Figs. 5 and 6 are elevation and plan respectively of a modified form of flap valve with means for adjusting the position of its center of gravity.

Fig. 7 is an elevational view of the back plate of the cavity forming the mixing chamber and guide for the jet enveloping valve.

Fig. 8 is a view of the jet enveloping valve as seen from below.

Fig. 9 is a side view on a larger scale of the regulating plug in the jet enveloping valve.

Fig. 10 is an end view of said plug from the left hand of Fig. 9.

Fig. 11 is a section thereof on line 11—11 of Fig. 9.

Fig. 12 is a section on line 12—12 of Fig. 9.

Fig. 13 is a right hand end view of said plug.

Fig. 14 is a side view, partly in section, of a modification of means for varying the counter-weighting of the flap valve which permits of slowing the movement of the flap valve at opening while diminishing its resistance to the entry of air when the flap valve is fully open.

The same letters of reference denote the same parts throughout the figure.

a represents the float chamber, the nature of which forms no part of the present invention, whence the gasoline or other liquid fuel passes to the jet *b* which discharges in the mixture chamber *b*¹. The jet *b* is preferably of a type permitting of regulation of its orifice such as described for example in my application for patent Serial No. 203433 filed 22nd November, 1917.

The mixture chamber *b*¹ is prolonged upwardly at *c*² to form a guide for the jet enveloping valve *c*. This valve, substantially

of the nature described in my prior application for patent Serial No. 104412 aforesaid contains a cavity d in which is a rotarily adjustable hollow plug e . The back plate c^4 5 of the mixture chamber has an opening A^1 (see Fig. 7) tapering below and affording passage to the engine manifold to which the carbureter is attachable by flange B of the projecting socket A . In the lowest position 10 of the valve c this valve closes the passage A^1 and the jet b projects fully into the cavity in the hollow plug e . At a slight rise of valve c the opening d^2 connects the interior of the plug e with the passage A^1 and slow 15 running mixture is supplied to the engine. At a point in the further rise of the valve c the jet b will no longer enter the valve but will discharge into the mixture chamber b^1 below the valve and the carbureter then operates 20 in the normal manner, the valve c acting as a throttle valve to the passage A^1 . The valve c is manually operated through a lever f pivoted at f^2 and against a counter spring f^1 , the end of the lever f having an eye f^4 engaging the pin f^3 passed through the lugs projecting upwardly from the valve c , all 25 substantially as set forth in my said application for patent aforesaid.

The back portion of the guide c^3 is preferably in the form of a segment of a cylinder 30 and the plate c^4 is fitted thereinto and secured by screws c^5 c^6 at the back and lower end. Closely behind the front plate c^7 of the guide c^3 the latter is extended laterally to 35 form two grooves c^8 c^9 (Fig. 2) in which slides vertically a plate g^3 for a purpose hereinafter described. The plate g^3 is held in its adjusted position by set screws c^8 c^9 inserted in tapped holes in the front plate c^7 40 of the guide c^3 .

The plate g^3 forms an upward extension of a face plate or hood g which projects forwardly as at g^6 from the mixture chamber and thence obliquely downwardly and rearwardly as at g^7 and ends in a projecting rib g^1 45 which engages in a recess in the base of the mixture chamber (Figs. 1 and 3). To permit of the insertion and removal of the hood g the grooves c^8 are widened or flared 50 toward their lower ends as shown in Fig. 3 to permit of the hood being tilted outwardly after the set screws c^8 have been loosened to disengage the projecting rib g^1 before drawing the hood downwardly to disengage the 55 plate g^3 from the grooves.

The front of the hood has an opening g^2 60 shaped to conform with that of the flap valve h which is pivoted on a transverse shaft g^4 passing through holes g^5 in the forwardly extended part g^6 of the hood.

The flap valve h is so weighted that in its normal position of rest it lies in the position shown in Figs. 1 and 4, closing almost completely the opening g^2 with the exception 65 of a small space at the lower end thereof, and

this is the position to which it will be returned by gravity when suction no longer operates to deflect it. So long as the valve c is sufficiently low to cover the jet b air enters through the orifice d^2 into the interior of the 70 plug e and passes out carbureted through d^1 to the engine through the opening A^1 . A slight raising of the valve c permits air also to pass to A^1 through the recess d^4 at the 75 base of the valve c . The valve c in these positions forms a stop which limits the inward movement of the flap valve h , but in proportion as the valve c is raised, the flap valve h may open more widely but the valve c still forms a stop thereto until the said valve has 80 risen to the position shown by the dotted line c^1 in Fig. 3 in which position the flap can fully open, the opening A^1 being also ther 85 fully uncovered by the valve c .

In this position of the valve c it may be 85 found that the flap valve h offers too much resistance to the entrance of air, for example owing to the rarity of the air at a great height being insufficient to open the flap valve, or to hold it open, to the extent desired. To overcome this defect, the following means are employed. k is a lever pivoted at k^1 to a lug on the front plate c^7 of the guide c^3 . The outer end of lever k is pivoted at k^2 to the forked head k^3 of a rod 95 k^6 guided in a fixed collar k^4 . Between the collar k^4 and the shoulder of the forked head k^3 is a spring k^5 tending to raise the rod k^6 to the position shown in full lines in Figs. 3 and 4.

The flap valve h carries a cam shaped projection h^1 . As the valve c rises above the position shown by the dotted line c^1 of Fig. 3 toward the position shown by the dotted line c^2 of Fig. 4, its upper end abuts against 100 and rocks the lever k , (see Fig. 3), thus pressing down the rod k^6 against the cam h^1 and pressing open the flap valve h .

The head h^2 of the flap valve h forms a 110 preponderant mass, and is hollowed as at h^3 so that the center of gravity of the flap valve is almost at the height of the axis of oscillation and lies more toward the interior of the hood g as the flap valve approaches its position of rest.

In the modification of the flap valve shown in Figs. 5 and 6 the head is detachable, divided into two portions h^{20} secured to lugs h^5 on the remainder of the flap valve by screws h^4 h^4 which permit of relative adjustment of the head with regard to the rest of the flap valve for modifying the position of the center of gravity. The two portions h^{20} may be turned about the screws h^4 120 as axes and secured in adjusted position by 115 tightening the said screws.

The flap valve shown in Figs. 5 and 6 has also a prolongation plate l intended for adjusting the amount of free opening left at g^2 when the flap valve is in its position of 130

rest. The plate *l* has a tongue *l*¹ movable in guides *l*² *l*² on the flap valve and securable in adjusted position by set screws *l*³.

By removing the plate *l* access can be had 5 to the end of the plug *e* when the valve *c* is in its lowest position, for the purpose of adjustment of the plug *e* if needed.

It will be seen that the mass which 10 constitutes the counterpoise of the flap valve *h* is disposed to the interior so that it exerts its greatest closing moment in the resting position of the flap valve but as the latter opens to full open position the masses moving through approximately 90° gradually 15 suffer reduction of their closing moment.

What I claim as my invention and desire to secure by Letters Patent of the United States is:—

1. In a carbureter comprising a mixing 20 chamber, the combination of a throttle valve movable longitudinally into and within said chamber a lateral hood on said chamber having an opening therein, a counter-weighted flap valve movable in respect of said open- 25 ing, the paths of movement of said flap valve

and throttle valve respectively intersecting each other whereby the throttle valve forms during part of its travel a variable stop for the flap valve, and means operable by the throttle valve toward the end of its upward 30 travel for holding the flap valves in open position.

2. In a carbureter comprising a mixing 35 chamber, the combination of a throttle valve movable longitudinally into and within said chamber a lateral hood on said chamber having an opening therein, a counter-weighted flap valve movable in respect of said opening, the paths of movement of said flap valve and throttle valve respectively intersecting each other whereby the throttle valve forms a variable stop for the flap 40 valve, and means for varying the effective area of said flap valve.

In witness whereof I have signed this 45 specification in the presence of two witnesses.

JOANNES PIAT.
